UNITED STATES PATENT OFFICE.

JULIUS G. HARRIS, OF PHILADELPHIA, PENNSYLVANIA.

STATION-INDICATOR.

No. 918,044.

Specification of Letters Patent. Patented April 18, 1909.

Application filed May 16, 1908. Serial No. 433,218.

To all whom it may concern:

Be it known that I, JULIUS G. HARRIS, a citizen of the United States of America, and resident of Philadelphia, Pennsylvania, have invented certain new and useful Improvements in Station-Indicators, of which the following is a specification.

This invention relates to certain new and useful improvements in station indicators designed primarily for use upon passenger cars to indicate to the passengers the next street to be reached or approached by the car.

The present invention has for its objects among others to provide a simple and improved construction which shall be efficient and reliable in its action, not liable to get out of order, in which the parts may be readily assembled or disassembled and by which an alarm will be sounded each time the indicator or register is changed, so as to call attention of the passengers to the fact in order that they may know when their street is to be reached. I employ a roller upon which the cloth or canvas is wound, and a flat faced roller upon which the canvas or cloth is wound from the first-named roller so that the inscription on the canvas will be exposed flat and in full view. Novel means are employed for operating the flat faced roller. The two rollers are geared together, and suitable means are employed for holding the rollers at each turn. The roller-actuating means may be operated by a cord or chain, or by other convenient means as may be found most expedient.

Other objects and advantages of the invention will hereinafter appear and the novel features thereof will be particularly pointed out in the appended claims.

The invention is clearly illustrated in the accompanying drawings which, with the numerals of reference marked thereon, form a part of this specification, and in which—

Figure 1 is a face view of the improved station indicator. Fig. 2 is a vertical longitudinal section through the same just back of the face plate or door. Fig. 3 is a vertical transverse section on the line 3—3 of Fig. 2 looking in the direction of the arrow. Fig. 4 is a view looking at the right hand end of Fig. 2 with the end plate removed.

Like numerals of reference indicate like parts throughout the several views.

Referring to the drawings, 1 designates a suitable case within which the working parts

are contained, said case being provided with a suitable front 2 which in this instance is shown as in the form of a door hinged to the bottom 4 of the case by suitable hinges 3. At one end the case is provided with a compartment 5 closed by a removable cap or end piece 6 held in place by suitable means as the screws 7. Within this compartment 5 is arranged a bell 8 and the hammers and accessories by which the alarm is sounded. The face or door 2 is provided with a suitable opening 9 which may be open or protected by a transparent plate so that the name of the street may be seen therethrough. The inner face of the door 2 is provided with a vertically curved recess 10 to permit of the operation of the parts soon to be described, and a suitable fastening device 11 may be provided for holding the front or door 2 in its closed position but allowing of opening of the same to permit access to the interior of the case for repairs or other purposes.

In opposite interior walls 12 are mounted the shafts 13 and 14 of the upper and lower rollers, the upper one of which (and the lower one also, if desired) is made flat faced so as to better present to the observer the name of the street on the cloth or canvas. 15 is the cloth or canvas attached at its ends to the said rollers so as to be wound upon and unwound therefrom, said cloth or canvas having printed, painted, or otherwise affixed thereon, as shown at 16 for instance, the names of the streets along the route traversed by the car on which the indicator is used. The shafts of these two rollers are geared together by means of the intermeshing gears 17 and 18. The walls 12, 12 and the rollers and other parts now to be described supported thereby, may be readily inserted into the case or removed therefrom when the door 2 is opened.

On the shaft 13 of the upper roller is fixed a collar 19 having a plurality of radial openings 20, one for each flat face of the roller, 100 while 21 designates a spring actuated pin actuated by the spring 22 within the vertical casing 23 secured to the adjacent wall 12, the lower end of this pin or rod being screw-threaded, as seen at 24, and provided with a nut 25 on said threaded portion. This pin automatically engages into the appropriate hole 20 of the collar 19 as the roller is turned, as will be readily understood, so as to insure the stopping of the roller in proper position 110

to present the name of the street squarely and flatly before the opening 9. The shaft 13 is extended at one end, and removably and adjustably secured thereto by means of a set 5 screw or the like, 24 is a collar 25 rigid with which are the disks 26 parallel with each other and connected by the pins 27, there being as many pins or rods as there are flat faces to the upper roller.

10 28 is a plate affixed to the wall, 12 or to the walls 29 at the back of the rollers, and having its outer end extended at a right angle, as seen at 30 in Fig. 3, where it receives the screw or other pivot 31 of the two curved 15 levers 32 and 33, seen best in Fig. 3, around which pivot is also coiled a spring 34, the ends 35 and 36 of which extend in opposite directions and the end 35 engages the pin 37 on the lever 33 and the end 36 engages the 20 pin 38 on the lever 32, as seen clearly in Fig. 3. On each of these curved levers is pivoted, as at 39, a pawl or detent 40, said pawls being oppositely disposed and normally extending substantially vertically, as seen best 25 in Fig. 3, and adapted when actuated, as will soon be described, to engage the pin 27 which stands in the path thereof. Each pawl has an arm 41 extending at substantially right angles therefrom at a point near its pivot 30 and adapted to engage a stop pin 42 projecting laterally from its adjacent curved lever. To each of the pawls 40 upon the side of its pivot opposite the arm 41 is attached, or bears thereagainst, a flat spring 43, the other 35 end of which engages a pin 44 on the curved lever to which the pawl is pivoted. All of this is clearly illustrated in Fig. 3.

The upper curved lever has its free end 40 provided with an opening 45 to which is attached one end of a cord, chain or the like 46 which passes downward through an opening 47 in the bottom 4 of the case and around a pulley 48 secured to the under side of said bottom and thence over another pulley 49 on 45 the bottom of the case and thence downward into position to be operated by the motorman, conductor or other authorized person. The lever 32 has in its free end an opening 50 to which is attached one end of a cord or 50 the like 51 which passes upward through an opening 52 in the top of the case and over a roller 53 secured upon the outer face of 55 said top and thence downward through an opening 54 in the bottom of the case and over suitable rollers secured to the under face of said bottom, as shown, and thence downwardly to a convenient point within the reach of the conductor, motorman or other authorized person. It will thus be 60 readily seen that each time one of the cords is pulled the curved lever to which it is attached will be moved on its pivot in the direction of the pull thereon, and the pawl 40 attached to said lever acting against its 65 appropriate pin 27 will move the disks 26

and consequently the roller on the shaft 13 in the proper direction. The cord should be pulled down and let fly back quickly, the spring 34 acting, by its appropriate arm, to return the lever to its normal position. The 70 spring 43 acting on the pawl serves to allow it to yield to pass the pin, when the spring returns it to its normal position ready for another operation. As the roller turns, the 75 rod or pin 21 automatically engages in its appropriate opening 20 to hold the roller against accidental movement. The engagement of said pin in the opening, however, is only such as to prevent this movement but not sufficient to prevent its being forced 80 backward into its casing against its spring as the shaft is rotated by the actuation of the cord and its appropriate lever etc.

In order to sound an alarm each time the 85 roller is operated I provide a bell 8 secured to the wall 55 and to the free end of each of the curved levers 32 and 33 I attach cords 57 and 56, respectively, the other ends of which extend through openings 58 in the wall 55 and over rollers 59 mounted therein, 90 the other end of each of said cords being connected to an eye or the like 60 of an arm 61 movable in a guide 62 on the outer face of the wall 55, said arm being provided intermediate its ends with an eye or the like 63 to which is attached one end of a spring 64, which is coiled, as seen at 65, around a suitable screw or the like 66 held in the wall 55 and the other end of each being suitably secured, as at 67, to the top and bottom of 100 the case, as shown. By this means, as the cord which operates the levers is pulled, say for instance cord 51 and the lever 32 is moved on its pivot so that its free end moves upward, the cord 57 will be pulled in the 105 direction indicated by the arrow 54 and the spring 65 put under tension. When the operating cord is released the spring pulls the cord 57 and consequently the arm 61 in the opposite direction, when the end or eye 60 110 thereof will be thrown quickly against the bell and sound an alarm. Hence at each partial revolution of the roller so as to change the name of the street, an alarm will be sounded to call the attention of the passengers to such change. Each arm 61 is 115 bodily movable, one end resting against the support of the spring 64, the other end attached to the cord, and between its ends said arm is attached to an end of the spring 64, 120 which spring-end moves as the cord is pulled upon. It will thus be observed that at each quarter revolution of the roller the name of the street is changed and the alarm sounded; it will be also observed that the actuating 125 mechanism operates in both directions so as to turn the roller upon which the name of the street is exhibited either forward or backward.

Modifications in detail may be resorted to 130

within the scope of the appended claims without departing from the spirit of the invention or sacrificing any of its advantages.

What is claimed as new is:—

- 5 1. In a station indicator, a rotatable shaft carrying a roller, oppositely disposed pivoted curved levers mounted to one side of said shaft and provided with means for rotating said shaft at intervals, cords connected directly with adjacent ends of said levers upon one side of their pivots, means receiving the opposite ends of said levers, lateral means on said levers adjacent their pivot, spring means coiled about and extending in opposite directions from said pivot and engaging said lateral means and an alarm having its operating means connected with said curved levers.
- 10 2. In a station indicator, a rotatable shaft carrying a roller, pins parallel with the shaft and rotatable therewith, oppositely disposed independently movable pivoted curved levers mounted on a common pivot, means connected directly with the free ends thereof and extending in opposite directions for moving said levers on their pivots, said levers being independently movable each on a common pivot spring actuated pivoted pawls mounted on said levers adjacent their free ends and
- 15 30 coacting with said pins to rotate the shaft, and a spring mounted upon the pivot of said levers and acting on said levers to return them to their normal positions said spring being common to both levers and disposed substantially parallel with the pawls.
- 20 35 3. In a station indicator, a rotatable shaft carrying a roller, pins parallel with the shaft and rotatable therewith, oppositely disposed pivoted curved levers mounted on a common pivot, means connected directly with the free ends thereof and extending in opposite directions for moving said levers on their pivots, said levers being independently movable each on a common pivot spring actuated pivoted pawls mounted on said levers adjacent their free ends and
- 25 40 45 coacting with said pins to rotate the shaft, and a spring mounted upon the pivot of said levers and acting on said levers to return them to their normal positions said spring being common to both levers and disposed substantially parallel with the pawls and an alarm sounding device connected with each of said levers and means coöperating with said shaft to
- 30 35 50 55 hold the roller after each partial revolution.
4. In a station indicator, a rotatable shaft

carrying a roller, means for operating the said shaft at intervals, embodying oppositely movable pivoted levers independently movable on a common pivot and pawls pivotally mounted on said levers, lateral means on said levers, cords connected directly with the free ends of said levers and extended in opposite directions for actuation to operate said levers the pivot of said levers being independent of said shaft, spring arms pivotally mounted on the pivots of said levers to engage said lateral means on the levers a bell, and spring actuated hammers for coöperation with said bell connected with the free ends of said levers.

5. In a station indicator, a shaft, a roller mounted thereon, parallel disks on said shaft having pins between them and parallel with the shaft, a plate affixed to the wall of the indicator having its outer end extending at an angle, a pivot independent of said shaft received in said angular end, oppositely disposed curved levers mounted on said pivot and independently movable, a spring coiled about said pivot with its ends extending in opposite directions, pins on said levers adjacent said plate with which the free ends of said spring engage, operating cords connected directly with the free ends of said levers, stop pins projecting laterally from said levers, and spring actuated pawls pivotally mounted on said levers and having lateral arms for engagement with said stop pins.

6. In a station indicator, a rotatable shaft, oppositely disposed curved levers mounted at one end on a common pivot and disposed around said shaft, means connected directly with the other ends of said levers, a spring coiled between its ends around the pivot of said levers with its portions upon opposite sides of the pivot extended in opposite directions, means on said levers adjacent their pivot with which the ends of said spring contact, pawls pivoted on said levers between their pivot and free ends, springs acting on said pawls near their pivots, pins on said levers for engagement with the free ends of said springs, each pawl having a right angled arm, and pins on said levers with which said arms engage.

Signed by me at Philadelphia, Pennsylvania, this 27th day of April, 1908.

JULIUS G. HARRIS.
